CIGARETTE PACKAGE AND BLANK OR
WRAPPER THEREFOR

Ferris Le Roy Francisco, New York, N. Y.

Application May 8, 1935, Serial No. 20,502

7 Claims. (Cl. 229—87)

My present invention relates to cigarette packages and blanks or wrappers therefor, and more particularly to cigarette packages of the so-called "cup" or "pouch" type such as are now extensively employed by the larger cigarette manufacturers in packing their most popular brands.

Cigarette packages of the type stated consist of an outer cup or pouch made from a blank composed of relatively stiff but easily crushable paper, said blank being folded and shaped to provide a cup or pouch having an open top and a closed and sealed bottom. The cigarettes are generally enclosed within a composite sheet of thin foil and paper, the said sheet being folded 10 in a characteristic manner at the opposite ends of the cigarettes, and the package so formed is enclosed within the cup or pouch with one of the interfolded ends of the composite wrapper exposed at the open end or mouth of the cup or pouch so that the said exposed interfolded portions may be readily torn away either wholly or in part in order to permit ready removal of the cigarettes. The filled package is usually sealed 20 by a revenue stamp extending over the top thereof with its opposite ends pasted to the opposite side walls of the package, the said stamp serving to hold the folded portions of the composite sheet in closed position.

Cigarette packages of the kind described are 30 made by complicated and expensive automatic machinery now in use by all the larger cigarette manufacturers and it will be apparent therefore, that any improvement in the package itself to have any chance of adoption, must be of such a 35 nature that it may be made by the present automatic machines and without material alteration or reconstruction thereof.

While the described type of package has been 40 extensively used, it is open to at least one serious objection, namely; it lacks the desired stability that such packages should possess to be entirely satisfactory, it being generally known that the present packages easily bend and crush transversely of their length when carried in the 45 pocket of the user, especially when some of the cigarettes have been removed therefrom, with the result that such bending or crushing breaks or crushes the cigarettes crosswise, rendering them unsmokable and thus entailing a loss to the 50 consumer to that extent.

With the above considerations in view, the 55 principal object of the present invention is to provide a cigarette package of the conventional cup or pouch type and an improved composite foil wrapper therefor that will be so constructed

as to materially resist transverse bending and crushing strains, in order to give further protection to the cigarettes, especially after some of them have been withdrawn from the package, and wherein the material of the package may 5 be more or less easily collapsed longitudinally, as along its vertical or longer axis, as the cigarettes are removed therefrom, whereby the size of the package may be gradually reduced as the cigarettes are withdrawn, while at the same time 10 the package becomes more and more resistant to transverse crushing and bending strains as it is collapsed.

A further object of the invention is to provide 15 a cigarette package of the kind described that may be made upon existing automatic cigarette packing machines without material alteration or reconstruction thereof, and wherein the appearance and size of the package are not noticeably altered, the latter being a desideratum of 20 great importance because of the known reluctance on the part of cigarette manufacturers to alter the shape, size or appearance of the package of an established tobacco brand.

I am aware that attempts have heretofore 25 been made to stiffen the walls of cigarette packages by including therein a strip of relatively heavy card-board, but such packages have not been entirely satisfactory and have not gone into general use, because the stiffener elements 30 employed do not permit the package to be readily folded longitudinally or in the direction of its length and thus reduced in size, as the cigarettes are withdrawn from time to time, and this is one of the desirable and important characteristics 35 of my improved package that distinguishes it from others and renders it more convenient and acceptable.

Briefly and generally stated my improved cigarette package comprises a cup or pouch closed 40 and sealed at one end and open at its other end, combined with a plurality of cigarettes wrapped within a composite foil and paper wrapper inserted within the cup or pouch, the said composite wrapper including a multiplicity of relatively narrow and connected stiffener elements 45 located within and extending longitudinally of the package and capable of permitting lengthwise folding thereof while materially increasing 50 the resistance to transverse or crosswise bending strains. From actual tests I have demonstrated that cigarette packages constructed in accordance with my invention are approximately fifty 55 percent more resistant to transverse or cross-

wise bending strains than the known packages of this type.

In the present application I have illustrated and described several different embodiments of the invention, but I do not wish to be understood as limiting myself to the precise forms shown, except as I may be limited by a fair interpretation of the appended claims, as it will be clear to others, after reading my disclosures, that changes or modifications may be made without departing from the spirit of the invention.

In order to enable those skilled in the art to understand and practice my said invention, I will now proceed to describe the same, reference being had to the accompanying drawings, where-in:—

Fig. 1 is a perspective view of a conventional "cup" or "pouch" type cigarette package.

Fig. 2 is a transverse sectional view on an enlarged scale, taken on the line 2—2 of Fig. 3, showing the package with one form of my improved stiffener incorporated therein;

Fig. 3 is a vertical section taken on the line 3—3 of Fig. 2;

Fig. 4 is a perspective view of a composite foil and paper wrapper blank having one form of stiffener element associated therewith;

Fig. 5 is a longitudinal sectional view of the blank taken on the line 5—5 of Fig. 4;

Fig. 6 is a perspective view of a slightly modified form of the blank shown in Figs. 4 and 5;

Fig. 7 is a transverse sectional view of the blank taken on the line 7—7 of Fig. 6;

Fig. 8 is a perspective view of a composite blank wherein the stiffener elements are formed from a corrugated sheet;

Fig. 9 is a view, similar to Fig. 8, showing a slightly modified arrangement of the corrugated sheet shown in Fig. 8;

Fig. 10 is a perspective view of a further modified form of corrugated sheet;

Fig. 11 is a perspective view of another form of stiffener strip;

Fig. 12 is a plan view of still another form of stiffener strip;

Fig. 13 is an end elevation of one form of means for forming the stiffener sheet of Fig. 12;

Fig. 14 is a transverse sectional view of a filled package of cigarettes with my improved stiffener incorporated therein, and

Figs. 15 and 16 are transverse sectional views of a cigarette package constructed according to my invention and showing two of the many ways in which such packages may be collapsed or folded longitudinally or in the direction of length of the cigarettes, while at the same time increasing the resistance to lateral or transverse bending strains.

Referring to Fig. 1, which is a perspective view of a conventional "cup" or "pouch" cigarette package, the reference numeral 1, indicates the outer wrapper sheet from which the cup or pouch is made, said wrapper being formed of a sheet of relatively stiff, but easily foldable material, such as paper, folded to provide a cup or pouch which is closed and sealed at its bottom and open at the top.

The cigarettes are enclosed or wrapped in a composite foil and paper wrapper blank with which my improved stiffener member is associated as will presently appear, and the package of cigarettes thus wrapped is inserted in the cup or pouch (or the blank from which the latter is formed is folded about the package) so that the

upper folded end of the package will be exposed at the upper open end of the pouch or cup with the foil portion of the wrapper exposed. In Fig. 1, the reference numeral 2, indicates the foil sheet of the composite wrapper which latter is usually closed providing two opposed pairs of inwardly directed folds 3 and 4, which are maintained in closed position by a revenue stamp 5, extending transversely across the same with the opposite ends of the stamp folded downward and pasted to opposite sides of the outer wrapper or cup or pouch as shown, thus completing the package. The package may be opened by ripping away all or a part of the folded portion or portions 3 and 4 of the composite wrapper, or by tearing off the stamp and opening up or unfolding the folded portions 3 and 4 of the composite wrapper.

In Fig. 4, I have shown one form of stiffener element made in accordance with my invention, associated with a composite wrapper of foil and paper. In said figure the reference numeral 2, indicates the foil sheet, 6 indicates the paper sheet and 7, indicates my improved stiffener element, the three sheets being arranged in superposed relation and joined to each other by separated lines or zones of adhesive 8. As will be seen the stiffener sheet 7, is narrower or of less width than the foil and paper sheets of the composite wrapper and is located centrally thereof, leaving portions of the longitudinal edges of the foil and paper projecting from each edge thereof to provide for the folding portions at the ends of the package when the cigarettes are wrapped in or enclosed by the blank as heretofore described.

The improved stiffener element 7, shown in Figs. 4 and 5, consists of a relatively thin sheet of stiff paper or veneer having closely arranged transverse cuts, score lines, or incisions 9, extending partially therethrough to provide therebetween a multiplicity of relatively narrow stiffener strips or elements 12, arranged parallel to each other and connected one to the other along easy folding lines formed by the thin connecting web at the base of the cuts or incisions 9. The sheet thus cut, scored or incised may, in consequence, be easily folded or bent along any of the weakened lines between any pair of stiffener strips in order to permit the cigarette package to be folded or collapsed along lines extending longitudinally thereof as more clearly shown in Fig. 15, which is illustrative of only one of many ways in which a cigarette package is thus folded or collapsed longitudinally by the user as the cigarettes are removed therefrom. I prefer to use for the stiffener strip a relatively thin, high calendered board of the type of so-called Bristol board in order not to materially increase the dimensions of the package and because this type of board has considerable inherent stiffness or strength.

It has been demonstrated by actual tests, that a cigarette package having the parallel stiffener strips associated with its wrapper as herein provided, may not only be easily folded or collapsed along parallel lines as described, but that the said strips materially strengthen the package and increase its resistance to transverse bending strains such as occur when the partially filled package is carried in a pocket of the user, and thus tend to prevent breakage of the cigarettes while in the package and consequent loss to the smoker.

Thus my improvement stiffener member, when associated with a cigarette package performs the two-fold function of permitting the partly empty package to be folded or collapsed longitudinally

or along lines extending parallel with the length of the cigarettes in the package, and also strengthens the package by increasing its resistance against transverse bending strains.

5 In Fig. 6, I have shown a modified form of stiffener element wherein I dispense with the paper sheet 6, and attach the foil sheet 2^a directly to the stiffener sheet 7^a, which may be equal in width to the foil sheet and wherein the cuts 10 or incisions 9^a extend only partially across the stiffener sheet. In this construction the portions of the foil and stiffener strips that extend longitudinally thereof and which lie outside the cuts or incisions are adapted to be folded in any 15 suitable manner in order to close the ends of the package.

Instead of forming the stiffener from an incised sheet, as previously described, I may employ one of a number of different forms or arrangements 20 of corrugated stiffener sheets, as shown in Figs. 8, 9 and 10 of the drawings.

In Fig. 8 the reference numeral 13 indicates the foil sheet, and 14 indicates the usual paper sheet which is associated with the foil sheet in 25 the production of the composite wrapper. In this arrangement, a corrugated sheet 15 with its attached backing sheet 16 is interposed between the foil and the paper sheets and connected thereto by lines or zones of adhesive 17.

30 In the construction illustrated in Fig. 8, the corrugated sheet 15 provides a multiplicity of stiffener strips formed by the ridges 18 of the corrugations which are connected together by the webs 19 between the ridges, thus permitting 35 the composite wrapper to be folded or collapsed along longitudinal lines, while at the same time the ridges of the corrugations serve to resist transverse bending or breaking strain.

The material from which the corrugated sheets 40 are formed, where such sheets are employed as above and as hereinafter described, is preferably composed of relatively thin, hard or highly calendered paper, as distinguished from the coarse and heavy paper usually employed in making corrugated containers. The reason for this 45 selection of the paper stock described, is to avoid, as much as possible, increasing the size and bulkiness of the package, and because a heavy paper stock is neither necessary or desirable.

50 In Fig. 9, I have shown another arrangement similar to that illustrated in Fig. 8, except that the backing sheet 16^a for the relatively thin but stiff corrugated sheet 15^a is located on the reverse side of the corrugated strip from that shown 55 in Fig. 8, and wherein the foil sheet 13^a is connected by lines or zones of adhesive 17^a applied directly to the ridges of the corrugation as well as to the foil sheet 13^a or to the paper sheet 14^a.

In Fig. 10 I have illustrated a further modification 60 wherein two corrugated sheets of relatively thin paper, 15^b, are arranged with their ridges 18^b in opposed relation to provide what might be termed a "succession" of hollow tubes 20 arranged parallel to each other and each of which 65 is connected to the other by intermediate thinner folding lines. In this arrangement shown in Fig. 10, the foil sheet is indicated by the numeral 13^b, and the paper sheet by the numeral 14^b, the said sheets being connected together by lines or zones 70 of adhesive 17^b, while the corrugated sheet 15^b is likewise attached to the sheet 14^b by lines or zones of adhesive 17^c.

In Fig. 11, I have illustrated a still further modification of the invention, wherein the stiffener consists of a plurality of stiffening strips 75

22, secured in spaced parallel relation to one face of a paper strip 23. In this arrangement I employ a foil sheet 24, which is adhesively attached to the paper sheet 23, along lines or zones 25, the adhesive being applied to the paper sheet 5 or the foil sheet, and may be applied also to the stiffener strips 22, the latter being arranged between the foil sheet 24 and the stiffener sheet 23. The strips 22, may be composed of any appropriate material, such as metal, wood splints, 10 cardboard or the like, and may be applied either to the paper or the foil sheet.

In Fig. 12, a still further modification is illustrated, and in this arrangement the stiffener consists of a sheet of relatively soft paper impregnated with a phenolic condensation product, such, for instance as Bakelite or the like, which is then compressed between a pair of hot forming surfaces, such as opposed toothed rollers 26, as shown in Fig. 13, to provide a strip having a 20 multiplicity of parallel stiffeners 27, joined together by relatively thin webs 28, constituting easily bendable folding lines. In this construction the stiffener strip is adhesively connected to a paper backing strip 29, which in turn is faced 25 with a foil sheet 30.

While I have illustrated and described herein several different forms of wrapper blanks of foil and paper having an associated stiffener, each of which embodies a multiplicity of relatively narrow 30 stiffener elements arranged in parallel relation, and wherein each is joined along easily foldable or bendable lines of thinner material, I do not wish to be understood as limiting myself to the arrangements and constructions shown, except as I may be limited by the appended claims, as obviously other constructions will readily suggest themselves to those skilled in the art.

In each construction shown and described it is to be understood that the composite wrappers are 40 to be prepared in the form of a continuous web supplied in roll form from which the wrappers may be cut as the composite web is fed into existing cigarette packing machines, thus my improved composite wrapping material may be used 45 in precisely the same way that the present wrapper material is used and without requiring any material changes in or additions to such packing machines.

What I claim is:

1. A cigarette package of the cup or pouch type, comprising a cup or pouch closed and sealed at one end and open at the other end, combined with a plurality of cigarettes wrapped within a composite foil and paper wrapper located within the cup or pouch, the said composite wrapper including a multiplicity of connected relatively narrow stiffener elements located within and extending longitudinally of the package and capable of permitting lengthwise folding thereof while 60 increasing the resistance to transverse bending strains, the end closure portions of said package being formed of flexible, foldable material.

2. A cigarette package of the cup or pouch-like type, comprising a cup or pouch closed and sealed at one end and open at the other, combined with a plurality of cigarettes wrapped within a composite foil and paper wrapper located within the cup or pouch, the said composite wrapper including a multiplicity of relatively narrow stiffener elements connected along weakened folding lines, said elements being located within and extending longitudinally of the package and permitting lengthwise folding thereof while increasing the resistance to transverse bending strains, 75

the end closure portions of said package being formed of flexible, foldable material.

3. The cigarette package defined in claim 1, wherein the foil portion of the composite wrapper is wider than the length of the stiffener elements.

4. The cigarette package defined in claim 1, wherein the said stiffener elements are of less length than the width of the foil sheet and are positioned between and transversely of the longitudinal edges of said sheet.

5. A composite wrapper for use in forming a cigarette package, including a foil sheet, a backing sheet and an associated stiffener sheet having a series of closely arranged parallel cuts or incisions extending transversely thereof to provide a relatively narrow stiffener element between each pair of said cuts or incisions, said stiffener

sheet being so arranged that the stiffening elements thereof will extend longitudinally of said package.

6. A composite wrapper for use in wrapping cigarettes, including a foil sheet, a backing sheet and a stiffener sheet associated therewith, said stiffener sheet having a plurality of closely arranged incisions in one face thereof to provide a multiplicity of relatively narrow stiffener elements, said stiffener elements being of less length than the width of the foil sheet, said stiffener sheet being so arranged that the stiffening elements thereof will extend longitudinally of said package.

7. The composite wrapper defined in claim 6, wherein the stiffener sheet is of less width than the width of the foil sheet.

FERRIS LE ROY FRANCISCO.
